UNITED STATES PATENT OFFICE.

WILLIAM F. BLANCHARD, OF DENVER, COLORADO.

PRICE-CARD HOLDING AND DISPLAYING DEVICE FOR STORE-SHELVES.

1,390,427.

Specification of Letters Patent. Patented Sept. 13, 1921.

Application filed April 20, 1920. Serial No. 375,371.

To all whom it may concern:

Be it known that I, WILLIAM F. BLANCHARD, a citizen of the United States of America, residing at the city and county of Denver, and State of Colorado, have invented a new and useful Price-Card Holding and Displaying Device for Store-Shelves, of which the following is a specification.

10 This invention relates to improvements in price card holding and displaying device for store shelves.

The object of the invention is to provide a device which is adapted to be secured to 15 store shelves and which is arranged to hold one or more cards having figures printed thereon, indicating the price of the articles displayed upon the shelf.

Further, to provide a device in the form 20 of a thin metal angle bar, the horizontally disposed member of which is secured to the under side of a shelf, adjacent its forward edge, its vertically disposed member extending parallel with the front edge of the 25 shelf and slightly spaced therefrom, to receive a price card which is inserted between the latter member and the edge of the shelf, the said latter or holding member acting in conjunction with the edge of the shelf to 30 securely clamp the price card, so as to prevent accidental displacement of the same, whereby the price of the article or articles displayed upon the shelf may be easily seen by purchasers.

35 These objects are accomplished by the device illustrated in the accompanying drawings, in which:

Figure 1 is a front view of a series of 40 store shelves equipped with the improved price card displaying device and showing the manner in which price indicating cards are held in said device.

Fig. 2 is a perspective view—full size— 45 of a portion of a shelf, showing the manner of securing the price card holding device to the forward portion thereof, a price card being shown in connection therewith.

Fig. 3 is a perspective view—full size— 50 of a portion of one of the card holders detached.

Fig. 4 is a sectional view, illustrating a slight modification in the construction of the clamping edge of the holder. And

55 Fig. 5 is a similar view, illustrating a still further modification of the said clamping edge.

Methods heretofore employed for displaying price cards so as to indicate the price of articles on store shelves, have proven unsatisfactory, as no satisfactory means of holding such cards has been employed. The present invention meets every requirement in such a device, by providing a fixed card holder, which is both practical and inexpensive, which is so positioned that it is 65 not likely to be injured by a clerk in placing goods upon the shelves or removing the goods therefrom, and which is adapted to hold a plurality of cards in the space between each two shelf partitions, so as to indicate different prices for various articles in the same shelf.

Referring to the accompanying drawings:

The numeral 1, indicates a series of ordinary store shelves, and 2, the card holder 75 constituting the present invention.

This card holder 2, comprises a thin metal angle bar, which may be of any desired length, but which is preferably of a length corresponding to the distance between the 80 usual vertical partitions 3, which support the shelves at intervals. The wings of this angle bar are approximately one-quarter of an inch wide, and the horizontal wing 4, is provided at intervals with nail or screw 85 receiving holes 5, and its vertical wing 6, terminates in a round edge or lip 7, which is obtained by bending a portion of the said wing inward upon itself throughout its 90 length, the bent-over portion 8, lying flat against the inner face of the wing, as clearly shown in Figs. 2 and 3.

The horizontal wing 4, of the angle bar, is secured to the under side of the forward edge of the shelf by screws or nails 9, which 95 are passed through the holes 5, and into the shelf, and its vertical wing lies parallel with the front edge of the shelf, but a slight distance therefrom, so that a very slight space

is left between the turned-in portion 8, of 100 said wing, and the edge of the shelf. This turned-in portion 8, acts in conjunction with the edge of the shelf, to clamp a price card 10, in position to indicate the price of articles placed upon the shelf, and for this 105 reason, the space between the edge of the shelf and the wing is so slight that the wing is outwardly sprung by the insertion of a card, and therefore bears under tension 110 against the card, by which the card is held against accidental displacement.

The improved device provides for the in-

sertion of two or more price cards in each holder, as may be required, to indicate different priced articles on the same shelf, and the insertion or removal of a card is easily 5 and quickly accomplished. The position of the holder upon the shelf not only renders it inconspicuous, but provides for the most effective display of the price cards, and as the holder is fixed, the only expense connected with the same is that incident to its 10 installment.

As each holder extends the distance between the two vertical partitions 3, a price card can be inserted at any point between 15 its ends; and this arrangement also provides for the insertion of long cards bearing advertising matter, as well as the price of the articles indicated.

In Fig. 4, is illustrated a slight modification in the form of the card-clamping lip of the holder, in which the bent-over portion 20 11, instead of lying flat against the inner face of the vertical wing 6, of the angle bar, is given a slight outward bend away from 25 the face of the wing, and as the lip 11, is resilient, it will yield slightly as a card is forced in between it and the edge of the shelf, and by its resiliency, together with that of the wing itself, a holding pressure 30 is exerted on the card sufficient for the purpose desired.

A still further modification is illustrated in Fig. 5, in which the clamping lip 12, of

the holder is formed by rolling a portion of the wing 6, upon itself, as shown, to produce a lip which is round in cross section. This form of lip has maximum rigidity and is therefore not easily bent by the careless insertion or removal of a card, and its round edge greatly facilitates the insertion 40 of cards.

Having described my invention, what I claim as new and desire to secure by Letters Patent, is:

The combination with a shelf, of a thin 45 resilient metal angle bar, made up of wings of unequal width, the narrower wing being provided with holes through which screws are passed to secure said wing to the under side of the shelf; the wider wing of said 50 angle bar extending parallel with the front edge of said shelf, and being bent inwardly upon itself to form a resilient lip which diverges from the wing from the bending point of the said lip to its longitudinal edge, 55 which is slightly spaced from the said front edge of the shelf, said resilient lip acting in conjunction with the front edge of the shelf to hold price cards inserted therebetween.

In testimony whereof I affix my signature 60 in presence of two witnesses.

WILLIAM F. BLANCHARD.
